Patented Dec. 28, 1920.

Inventor

Joseph Soss

By his Attorneys

Edgar Hale & Co.

UNITED STATES PATENT OFFICE.

JOSEPH SOSS, OF NEW YORK, N. Y.

HINGE.

1,363,372.

Specification of Letters Patent. Patented Dec. 28, 1920.

Application filed June 26, 1920. Serial No. 391,861.

To all whom it may concern:

Be it known that I, JOSEPH Soss, a citizen of the United States, and residing at New York, in the county of New York and State of New York, have invented certain new and useful Improvements in Hinges, of which the following is a specification, such as will enable those skilled in the art to which it appertains to make and use the same.

This invention relates to hinges and particularly to devices of this class designed to be used in connection with doors of motor vehicles, but which may also be used in connection with other doors or swinging members, and the object of the invention is to provide a die-cast hinge or hinge member of the class specified, and means for reinforcing and strengthening said hinge or hinge member by a sheet metal part fashioned to conform with the general form of the hinge or hinge member thus materially decreasing the cost of production of the hinge member and yet producing an article of the class described having the desired strength and durability; a further object being to provide reinforcing and strengthening means composed of a plurality of sheet metal parts secured together and which form a part of the complete die-cast hinge, and with these and other objects in view the invention consists in a device of the class and for the purpose specified, constructed as hereinafter described and claimed.

The invention is fully disclosed in the following specification, of which the accompanying drawing forms a part, in which the separate parts of my improvement are designated by suitable reference characters in each of the views, and in which:

Figure 1 is a plan view of the separate parts of my improved hinge connected with a door and door frame with part of the construction broken away and in section;

Fig. 2 a horizontal sectional view through the complete hinge with parts in a different position from that shown in Fig. 1 and with part of the construction broken away;

Fig. 3 a face view of one of the members of the hinge shown in Figs. 1 and 2;

Fig. 4 a perspective view of the reinforcing means employed in the construction shown in Figs. 1 to 5 inclusive;

Fig. 5 a section on the line 5—5 of Fig. 3 with part of the construction broken away;

Fig. 6 a view similar to Fig. 3 but showing only a part of the construction and showing a modification;

Fig. 7 a view similar to Fig. 3 but showing only a part of the construction and showing another modification; and,

Fig. 8 a partial section on the line 8—8 of Fig. 7.

In Figs. 1 and 2 of the drawing, I have indicated at 10 a part of the door frame and in Fig. 1, I have indicated at 11 a part of a door, and my complete hinge comprises a hinge member 12 which, in the construction shown is secured to the door frame 10 and hinge member 13 which is secured to the door 11 and movable therewith. The separate hinge members 12 and 13 are secured together and movable one upon another on a pivot 14 which passes through the separate hinge members.

The invention described and claimed herein relates particularly to the hinge member 12 and in Figs. 1 to 5 inclusive, I have shown one form of construction for carrying my invention into effect.

The hinge member 12 is die-cast and comprises a main body portion 15 having screw apertures 16. One end of the body portion 15 is enlarged and substantially hook-shaped in form as shown at 17 and said end portion is provided, in the form of construction shown, in said figures, with two projecting and substantially hook-shaped ears 18 having apertures 19 through which the pivot pin 14 is adapted to pass.

In constructing the hinge member 12 I provide means for reinforcing and strengthening the same which, in the construction shown in Figs. 1 to 5 inclusive comprises a main sheet metal plate 20 and a supplemental sheet metal plate 21 secured to the main plate 20 by riveting, welding or otherwise. The main plate 20 is approximately rectangular in form and the side edge portions thereof are provided with inwardly

2
directed flanges 22, thus fashioning said plate into substantially channeled or U-shaped formation. The end 23 of the plate 20 is bent into substantially hook-shaped 5 form and the free edge 24 thereof is slightly curved to correspond with a similar curvature in the member 13 of the complete hinge to form a neat and finished appearance between the separate members of the hinge 10 when in their extended position as shown in Fig. 2.

The supplemental plate 21, or the end portion 25 thereof, is fashioned to conform with and fit within the corresponding end 15 portion of the main plate 20, while the other end portion of said supplemental plate is fashioned to form two substantially hook-shaped members 26 joined by a central portion 27 inwardly of the free ends of said 20 members and the central portion 27 is fashioned to conform with the hook-shaped end portion 17 of the main plate 20, as clearly shown in Figs. 2 and 5 of the drawing, while the parts 28 of said members at the opposite 25 sides of the central portion 27 are located inwardly of the part 20 to form a space 29 which is filled in with the die-cast material of the hinge in making up the complete hinge.

30 It will be noted that the flange portions 30 of the supplemental plate 21 extend through the members 26 and are of such formation as to conform with the shape of the ears 18 of the complete hinge and form outer 35 facings 31 therefor, as clearly shown in Fig. 3 of the drawing, and the parts 28 of the members 26 extend partially around the periphery of the ears 18 of the hinge member as shown at 32 in Fig. 5 of the drawing to reinforce that portion of the complete 40 hinge member through which the pivot pin passes.

In forming the completed hinge member 12 and after the reinforcing means comprising the main and supplemental plates 20 and 21 have been secured together to produce the 45 result shown in Fig. 4, the same is placed in a suitable die or mold and the complete hinge member is formed by a die-cast body 50 33 which fills in the channeled portion of the members 20 and 21 as well as the channeled portions of the members 26 of the plate 21 and the result shown in Figs. 1 to 3 inclusive and in Fig. 5 is produced.

55 In forming the screw-holes or apertures 16, I preferably form the countersunk portions 34 of such holes in the die-cast portion of the hinge member, after which the remaining portions of the holes are either 60 punched or drilled through the plates 20 and 21.

In the construction shown in Fig. 6 I have shown a hinge member 12 made in a slightly different manner by simply fash-

ioning the two substantially hook-shaped 65 ears 18 into one unit or member 35 and in forming this construction I may employ the same reinforcing means as employed in the construction shown in Figs. 1 to 5 inclusive by simply filling in the channeled portion between the members 26 with the die-cast material 33 of the complete hinge member, it being understood that the pivot pin apertures 19 will extend through the entire member 35 in the construction shown 75 in Fig. 6.

In the construction shown in Figs. 7 and 8 of the drawing I have shown the hinge member 12 made in the same general form as that of said hinge member shown in Figs. 80 1 and 5 inclusive, except that the supplemental reinforcing plate 21 is omitted and the plate 20 alone is employed. In this form of construction the main body portion 15 as well as the substantially hook-shaped 85 ears 18 of the hinge member 12, independent of the plate 20, may be made of die-cast, forged or otherwise, fashioned material which is secured to the plate 20 in any desired manner.

90 From the foregoing it will be seen that in constructing the hinge member 12, I may employ a reinforcing means comprising a single piece of sheet metal bent into the desired form, or I may employ two or more 95 sheet metal parts secured together and combined with another body, preferably a die-cast body to form the complete hinge member, and while I have shown a hinge member of specific form or design, it will be understood that I am not necessarily limited in 100 this respect, and various changes in and modifications of the construction herein shown and described may be made, within the scope of the appended claims, without 105 departing from the spirit of my invention or sacrificing its advantages.

Having fully described my invention, what I claim as new and desire to secure by Letters Patent, is:—

110 1. A die cast hinge member of the class described composed of a die cast body, one 115 end portion of which is enlarged and extends at an angle to the main body portion thereof, a sheet metal plate forming a facing for one side face and the top and bottom faces of said die cast body, and a supplemental sheet metal plate within said first named plate and extending through said die cast body and forming a facing for a portion of 120 the enlarged end of said die cast body.

125 2. A die cast hinge member of the class described composed of a die cast body, one end portion of which is enlarged and extends at an angle to the main body portion thereof, said enlarged end being of less transverse dimensions than the main body portion of said body, a sheet metal plate form-

ing a facing for one side face and the top and bottom faces of said die cast body, and a supplemental sheet metal plate within said first named plate and extending through 5 said die cast body and forming a facing for a portion of the enlarged end of said die cast body.

In testimony that I claim the foregoing

as my invention I have signed my name in presence of the subscribing witnesses this 10 25th day of June 1920.

JOSEPH SOSS.
